United States Patent

Des. 240,572
Patented July 20, 1976

240,572

BELT-ATTACHED TOOL HOLDER

Paul E. Worsham, 3433 Calvin Ave.,
San Jose, Calif. 95124

Filed Dec. 9, 1974, Ser. No. 530,513

Term of patent 14 years

Int. Cl. D2—07

U.S. Cl. D2—400

FIG. 1 is a perspective view of a belt-attached tool holder showing my new design;

FIG. 2 is a front elevational view of the holder shown in FIG. 1;

FIG. 3 is a right side elevational view of the holder shown in FIG. 1;

FIG. 4 is a rear elevational view of the holder shown in FIG. 1; and

FIG. 5 is a bottom plan view of the holder shown in FIG. 1.

I claim:

The ornamental design for a belt-attached tool holder, substantially as shown and described.
